UNITED STATES PATENT OFFICE.

JOHN C. FOX, OF MCKEESPORT, PENNSYLVANIA.

FALL-BLOCK.

1,091,497.

Specification of Letters Patent. Patented Mar. 31, 1914.

Application filed October 20, 1913. Serial No. 796,119.

To all whom it may concern:

Be it known that I, JOHN C. FOX, a citizen of the United States, residing at McKeesport, in the county of Allegheny and 5 State of Pennsylvania, have invented certain new and useful Improvements in Fall-Blocks, of which the following is a specification.

My invention aims to provide a fall block 10 constructed to provide a maximum safety from personal injuries and also to greatly reduce the liability to such injuries to those required to handle it. Many accidents are 15 caused when using these blocks practically through the carelessness upon the part of the workmen using them, in grasping the cable while the same is in motion, or by grasping the cable to assist in attaching the block while not in motion but which may be accidentally started.

In my design, I have provided a covering 20 for the normally open top portion of the block, which will absolutely prevent the in-drawing of the fingers or the hand to the 25 main sheave wheel. This cover portion extends between the two side plates normally, used and above the main sheave wheel and is 30 apertured for the passage of the ropes or cables. In its preferred form, I make this cover portion of substantially plane formation and disposed in a horizontal relation when the block is operatively suspended, whereby it will be noted that the cables and 35 cover portion are substantially at right angles to each other, thereby obviating all crowding or wedging and the workman being caught unawares with his hands in a dangerous position. I have also provided two idler sheaves, disposed opposite each 40 other and adjacent the cover portion to prevent abnormal wear of the cable by its engagement with the walls of the apertures through the cover portion, due to its natural swinging or oscillation when in use. In this 45 latter form, I desirably extend the cover portion well around the corners of the block to also protect the workmen from the action of these idler sheaves.

Further objects of my invention will be 50 apparent from a detailed description of the accompanying drawings, in which similar characters of reference designate corresponding parts, and in which:

Figure 1 is a view showing my fall block 55 in section, such section being taken directly behind one of the face plates, and, Fig. 2

is a section taken on line 2—2 of Fig. 1 and looking in the direction of the arrows.

In embodying all of the above objects in one device, I have provided opposing face 60 plates 1 of substantially triangular form having flanged portions 2 at their upper ends, such flanged portions extending well around the upper corners of the plates as shown at 2^a. Reference to Fig. 2 will show 65 that the block, as a whole, is split centrally whereby the face plates can be made interchangeable. The main sheave 3 is journaled at approximately a central point between these two face plates upon a shaft 4 provided 70 with threads 5 at its opposite ends and securely held in position by means of nuts 6, each locked against rotation by a cotter pin 7. The main sheave itself rotates about a bushing 8 of somewhat greater length 75 than the width of the hub portion of the sheave itself, thereby preventing a binding action when the nuts 6 are drawn tight. The cover portion formed by the coöperation 80 of the flanges 2 and 2^a, is provided with apertures 9 through which the rope or cable 10 is adapted to pass, these apertures being arranged to be about midway between the working surface of the main sheave 3 and idler sheaves 11 carried between the adjacent 85 upper corners of the face plates. These apertures are of a size to permit free passing therethrough of the cable 10 and the purpose of the idler sheaves is to prevent the cable 10 from entering or leaving the fall 90 block in anything but its true path of travel or in other words, to prevent this cable from entering or leaving in any manner except in true alinement with the grooves of the main sheave, whereby wear upon the cable itself 95 is reduced, by preventing its engagement with the outside walls of the apertures 9.

It will be apparent that due to the natural swinging or oscillation of a fall block when in use, one or the other of the idler sheaves 100 11 will come into play to insure the correct path of movement of such cables and will prevent excessive swinging or oscillation. As will be seen from the drawings, these idler sheaves are mounted upon bolts 12 each 105 carrying a bushing 13 constructed similar to the bushing 8. Nuts 14 are also provided to assist in binding the two face plates together in a manner similar to the nuts 6. The lower portions of these face plates 110 carry between them a hook 15 of well known construction, such hook being provided with

a swivel mounting as is customary in these devices. A supporting bolt 16 having its ends threaded and carrying nuts 17 is provided and has a central aperture through which the shank of the hook is adapted to pass and to be headed over as shown at 18. In this manner the hook may rotate about its axis or may be made to oscillate about the bolt 16.

- 10 From the above description taken in connection with the accompanying drawings, it will be apparent that a type of device has been provided where it is practically impossible for a workman to injure himself, owing 15 to the elimination of such inclined wedging surfaces as are common to these blocks, at the top or entrance end thereof. Further, idler sheaves 11 have also been provided for protecting the cable itself against wear, 20 these sheaves being also guarded by the housing or flanged portions 2^a.

What I claim, is:

1. A fall block comprising a pair of side plates, a main sheave journaled between said 25 side plates, a cover portion spanning the distance between said side plates at the top portion thereof, said cover being apertured for the sheave ropes, a swiveled hook carried between said plates at the bottom thereof, and a plurality of idler sheaves mounted 30 between said plates directly beneath said cover portion.

2. A fall block comprising a pair of side plates, the upper portions of said plates being substantially horizontal when the block 35 is held operatively suspended, a cover portion of substantially plane formation spanning the distance between the upper portions of said plates, a sheave journaled between said plates, said cover being apertured 40 for the sheave ropes, and a hook mounted between said plates at the bottom thereof.

3. A fall block comprising a pair of substantially triangular side plates having one 45 of their legs disposed in a horizontal position when the block is held operatively suspended, a cover portion of substantially plane formation spanning the distance between the horizontally disposed portions of 50 said plates and extending an appreciable distance around the corners thereof, a main sheave journaled between said side plates, said cover portion being apertured for the 55 sheave ropes, a pair of idler sheaves mounted between said plates, one in each of said protected corners, and a hook mounted between said plates at the bottom thereof.

In testimony whereof I affix my signature in presence of two witnesses.

JOHN C. FOX.
